W. WILLIS.
AUTOMOBILE SIGNAL.
APPLICATION FILED MAY 21, 1921.

1,392,731.

Patented Oct. 4, 1921.

Inventor

William Willis

By Heratio E. Bellows

Attorney

UNITED STATES PATENT OFFICE.

WILLIAM WILLIS, OF PAWTUCKET, RHODE ISLAND.

AUTOMOBILE-SIGNAL.

1,392,731.

Specification of Letters Patent.

Patented Oct. 4, 1921.

Application filed May 21, 1921. Serial No. 471,343.

To all whom it may concern:

Be it known that I, WILLIAM WILLIS, a citizen of the United States, residing at Pawtucket, in the county of Providence and State 5 of Rhode Island, have invented certain new and useful Improvements in Automobile-Signals, of which the following is a specification.

My invention relates to signals for automobiles and other vehicles.

The essential objects of my invention are facility of operation; portability and adjustability for attachment and use; inexpensiveness of construction; and certainty and accuracy of spring action.

To the above ends essentially my invention consists in such parts and in such combinations of parts as fall within the scope of the appended claims.

20 In the accompanying drawings which form a part of this specification,

Figure 1 is a front elevation of my signal, Fig. 2, a section of the same on line 2—2 of Fig. 1,

25 Fig. 3, a partial section of the same in extreme open position taken on line 3—3 of Fig. 2, and

Fig. 4, a section on line 4—4 of Fig. 1.

Like reference characters indicate like 30 parts throughout the views.

In detail my device comprises a vertical shaft 7 provided with a longitudinal channel or recess 8 extending from the top of the shaft to an intermediate portion thereof and 35 forming a longitudinally disposed lateral opening 9. The channeled portion forms a housing or seat for an index arm open along one side and comprising front and rear walls 11 and one side wall 12. In the bottom of the 40 recess is a transversely disposed pin or pivot member 14 passing through an opening 15 near the lower end of the index arm 16 whose upper end projects beyond the housing and in this instance terminates in an arrow head 45 point 17. The recess 8 is somewhat deeper at its closed side as at 19 and from this point continuing upwardly some distance the wall 12 is cut away to form a longitudinally disposed slot 20 to permit passage therethrough 50 of the lower end of the index arm when the latter is tilted. Extending downwardly in the lower end of the shaft from the portion 19 of recess 8 is a cylindrical hole 22 transversely of whose lower portion extend a 55 screw or pin 23 to which is attached the lower

end of a helical spring 25 in which upper end is a loop 26 through which passes one end of a link 27 whose other end passes through an eye or ring 28 fast to the rear side of the shaft 7 near its lower end. For housing purposes a flat casing 30 is provided extending laterally from the shaft and fixed to the latter by attaching screws 34 passing through an extension 35 on the lower end of the casing. The top of the casing is open 60 as well as the side adjacent the shaft 7 whereby a chamber 36 is formed to allow room for the travel of the arm when the latter is tilted. A bracket is provided having a base 38 fixed by an attaching screw 39 to the side of 70 the shaft and extending downwardly within the casing to the upper portion of the opening 20 where it forms a stop against excessive depression of the arm 16. Extending horizontally from the bracket base is a rectangular body or frame 40 registering with the top of the casing, transversely of which is a pintle 41 upon which is mounted a pulley or roller 42. At intervals in the side of the shaft 7 are guide eyes 44, and near the 75 top of the former is fast a pulley 47. A flexible member 49 has its lower end attached to the eye 28 and passes over the roller or pulley 42, through the guide eyes 44, and over the pulley 47. Its end which depends from 80 the pulley has attached thereto a handle 50.

The device may be attached by screws therethrough or otherwise to any part of an automobile or other vehicle at a point convenient for the driver to grasp the handle 90 50. Normally the parts are in the position shown in Figs. 1 to 3 inclusive. By drawing the handle 50 the arm is movable to any desired radial position within an arc of ninety degrees. In Fig. 3 the arm 16 is shown 95 horizontally or in position to indicate that the driver is going to turn to the right. An intermediate position of the arm is a signal to the left. The construction, arrangement, and relative location of the spring 25 permits free and effective action of the arm.

I claim:—

In a device of the character described, a shaft provided with a longitudinal recess extending from an intermediate portion to its 105 top and one side, and with a vertical hole extending downwardly from the recess, an indicator arm pivotally mounted at a short distance from one end in the lower portion of the shaft normally seated in the recess, a helical 110

spring in the hole, a pin on the lower portion of the hole engaged with the lower end of the spring, an eye on the side of the arm carrying the other end of the spring, said shaft 5 being provided with a lateral slot to permit the passage of the spring, and allow play for the inner end of said arm, a pulley on the shaft above the eye, guides on the shaft

above the pulley, a second pulley on the shaft above the guides, and a flexible member attached to the eye and engaging the pulleys and the guides.

In testimony whereof I have affixed my signature.

WILLIAM WILLIS.
